United States Patent

Des. 235,627
Patented July 1, 1975

235,627

DIGITAL VERNIER CALIPER

Kenju Uchino, Utsunomiya, Japan, assignor to
Yehan Numata, Yokohama, Japan

Filed July 23, 1973, Ser. No. 381,662

Term of patent 14 years

Int. Cl. D10—04

U.S. Cl. D10—73

FIG. 2

FIG. 1

FIG. 3

FIG. 4

FIG. 5

FIG. 6

FIG. 1 is a front elevational view of a digital vernier caliper showing my new design;

FIG. 2 is a rear elevational view thereof;

FIG. 3 is a bottom plan view thereof;

FIG. 4 is a top plan view thereof; and

FIG. 5 is a left side elevational view thereof; and

FIG. 6 is a right side elevational view thereof.

I claim:

The ornamental design for a digital vernier caliper, as shown.
